ADIEL Y. DODGE, OF SOUTH BEND, INDIANA

ELECTRIC SWITCH

Application filed April 29, 1929. Serial No. 358,782.

This invention relates to electric switches and may be characterized as an improvement in electric switches of the type illustrated and described in the copending application 5 of Harris C. Roth, Serial No. 358,792, filed April 29, 1929.

The present invention is not, however, limited to use with the features of the above application, but may be employed as suitable or desired.

The primary object of the present invention is the provision of an improved envelope and liquid separator and, more particularly, the provision of a generally improved and simplified envelope that may be formed more economically and expeditiously.

Another object is to reduce the operations and labor involved in the formation of these 20 envelopes and to provide an envelope structure permitting the use of heavier glass than heretofore practicable.

Another object is to improve the evacuation of the containing tube or envelope.

Another object is to improve the mounting and actuating means for the switch.

Further objects and advantages of the present invention will appear from the following detailed description, taken in connection with the accompanying drawing, in which:

Figure 1 is a side elevational view of a switch and actuating means, embodying the present invention and in closed circuit position;

Figure 1A is a fragmentary side elevational view of the tubular stock of which the envelope is preferably formed.

Figure 2 is a view similar to Figure 1, 40 showing the switch tilted to open circuit position;

Figure 3 is a horizontal sectional view, taken on the line 3-3 of Figure 1;

Figure 4 is a transverse section, through 45 one of the legs of the device, taken on the line 4-4 of Figure 3;

Figure 5 is a fragmentary cross-section through the make and break connection between the legs of the device, taken on the 50 line 5-5 of Figure 3;

Figure 6 is a section taken on the line 6-6 of Figure 3;

Figure 7 is a sectional view, similar to Figure 6, showing the switch tilted to open circuit position;

Figure 8 is a view similar to Figure 3, of another form of the invention;

Figure 9 is a sectional view, taken on the line 9-9 of Figure 8;

Figure 10 is a view similar to Figure 9, 60 showing another shape for the make and break connection between the legs of the device; and

Figure 11 is a diagrammatic view, showing the method of obtaining better evacuation.

In the embodiment of Figures 1 to 7, inclusive, 10 indicates the bulb or enclosing envelope, which is shown of generally U-shaped formation, with the opposite legs 11 and the make and break connection 12 between these legs. The bulb or envelope 10 is preferably made of glass, although other suitable or preferred materials, having the desired properties, are contemplated.

Where the bulb is of glass, the glass is preferably of a character having high heat and arc resisting properties, although this may vary. For example, with the thicker glass permitted by the present invention, a less expensive glass or other material might be suitable.

The tube or envelope 10 is adapted for holding and permitting movement or flow of the mercury or other conducting body 14 for the purpose of opening and closing the electric circuit. According to the present invention, the envelope 10 is preferably formed of a single length of straight glass tubing, indicated at 5 in Figure 1A, which tubing is heated and bent to the desired configuration. The form of the envelope may vary from the particular U-shaped configuration shown in Figures 1 to 10, but the particular configurations shown are illustrative of liquid switch envelope formations that may be formed of a single length of glass tubing and which are adapted for holding the mercury or other conducting body and for separating or dividing this body and permitting move-

ment of the separated portions toward and away from each other in closing and opening the switch.

These are important aspects of the present invention and variations in the form or contour of the envelope obtaining these advantages are contemplated.

In the embodiment of Figures 1 to 7, the straight tube 5 of Figure 1A is heated and bent to generally U-shaped form. The opposite ends may be drawn and sealed, as at 15, to close the outer ends of the legs 11 and it is to be understood that the tube or envelope may be evacuated as, for example, before sealing one of the ends at 15. Where the make and break connection is reduced in section, as shown in Figure 1, or decreased in width, as also shown in Figure 1, or where the make and break connection is humped at 30, as shown in Figures 6 and 7 or other formations different from the normal condition of the tubing, these formations are inexpensively and expeditiously obtained by drawing the tubing or pressing it to the desired configuration either with or separately of the bending operation. This forming of the envelope by bending a single length of tubing, together with the formation of the reduced or changed sections, humped portions and the like by simple drawing or forming operations materially simplifies production and reduces the cost. At the same time, by forming the envelope in this manner, I find that the envelope may be made of thicker glass than practical where the bulb is blown with the separate wells blown directly out of the walls of the envelope or made up entirely separately and fused to the main body of the envelope, as heretofore.

40 The electrodes 16 and 17 may be sealed through the legs 11 with their inner ends disposed to be connected by the mercury body 14 when the device is in the position shown in Figure 1 and to be disconnected when the device is in the position shown in Figure 2. It will be understood that the electric circuit controlled by the switch is connected with the electrodes 16 and 17 and that this circuit is opened and closed by tilting the device from closed circuit position shown in Figure 1 to open circuit position shown in Figure 2, and vice versa. With the device shown in Figure 1, the amount of mercury or other conducting fluid within the tube is sufficient to fill the make and break connection 12 with the opposite ends of the body extending into the legs 11 sufficiently to have good contact with the electrodes 16 and 17 and to form an electric connection between these electrodes through the body of mercury. When the device is tilted from the position shown in Figure 1 to the position shown in Figure 2, the make and break connection 12 separates the body of mercury 14, as indicated at 20 in Figure 7 into two bodies 14^a and 14^b, which, as the

device is tilted to open circuit position, move away from each other toward the closed ends of the legs 11 and, in tilting the device to closed circuit position, move toward each other and meet at the point of separation or make and break point 20. This movement of the separated bodies 14^a and 14^b away from each other in the opening operation of the switch and toward each other in the closing operation of the switch substantially doubles the speed of make and break. This tends to reduce arcing and to produce a clean make and break.

Another feature of importance of this construction is that after the point of break is established the topmost portion of the bodies of conducting liquid separate and move away from one another in a direction at right angles to the plane of tilt. The tangent at the point of the curved bend where the break occurs is at right angles to the plane of tilt and therefore has no inclination, regardless of the tilt. The effective force of gravity is least at this point. Traveling in the path that the mercury moves, the rate of tilt or the inclination increases both ways from this point. That is, as the tube is tilted from a horizontal position the tangents at successive points around the curve from the point of make and break make increasing angles with the horizontal. Therefore, after the break takes place, the mercury columns, and more particularly the mercury columns at the broken ends, encounter an increasing slope whereby the separating movement of the two bodies is accelerated. This acceleration is further increased due to the fact that when the break is established the cohesive force of the mercury is released, and substantially the entire, or a relatively great part of the force of gravity acting on the mercury bodies, due to the tilted position of the device, is operative to effect a quick separation thereof, whereas just before the mass of mercury separated the cohesive force of the mercury opposed the force of gravity. Thus in my construction the effective force acting to separate the liquid is materially increased the instant the break is completed and it continues to increase as the broken ends separate. As the broken ends move away they continually encounter a steeper incline. It will be understood that the sharper the horizontal curvature of the connection 12 the greater will be the proportion of increase.

The reduction in section of the connection 12 produces, in effect, a relative enlargement in section of the legs 11, as shown, which augments the freedom of separating movement of the bodies 14^a and 14^b, but this may vary. With the tube formation of the mercury channel, additional separator bodies and the like may be omitted and the tube, in addition to forming the separator, as well as the enclosure, encloses each mercury body 14^a and 14^b.

- 14^b, where the main body of mercury is separated, separately and prevents communication between these bodies, except through the make and break connection 12.
- 5 The sectional contour of the connection 12 may be of any suitable or preferred shape. In the embodiment illustrated in Figures 1 to 7, the sectional width of this connection is reduced, as shown particularly in Figure 5.
- 10 The relatively narrow or reduced width W (Figures 3 and 5) relative the depth or vertical dimension of the interior of the connection 12 reduces the width of the mercury body at the point of make and break 20 and 70
- 15 this gives a blunter meniscus 25 to the two ends of the separated bodies 14^a and 14^b, as more fully explained in the copending application of Harris C. Roth, Serial No. 358,792, filed April 29, 1929. This blunter shape or 80
- 20 meniscus 25 at the make and break ends of the bodies 14^a and 14^b disposes a larger body of mercury at the actual point of make and break and this reduces or avoids undue heating and produces a better make and break 85
- 25 than heretofore. This improvement in the making and breaking action of the switch and the reduction in heating effect at the actual make and break point avoids or reduces injury to the enclosure 10 and enables 90
- 30 carrying higher wattages than heretofore possible in switches of this type. Commonly, where the height of the channel or fluid holding and separating passages is no greater than the width of said passage at 95
- 35 the point of make and break, a rounded and even generally pointed meniscus is produced at the opposite ends of the separated fluid body. Two pointed or even two rounded ends will make and break with a point contact and the reduced body of mercury or 100
- 40 other conducting fluid at this contact in the make and break operation causes undue heating and arcing.
- The present invention is not limited to a 105
- 45 connecting portion of narrow width and I have, therefore, shown fragmentarily, in Figure 10, an embodiment in which this make and break connection 12' is of generally circular section. The section of Figure 10 is similar to 110
- 50 the section of Figure 5 and one of the legs of the tube is indicated fragmentarily at 11'. As already explained, with the present invention, the reduced section 12' of Figure 10, as well as the narrowed section 12 of Figures 1 to 7 115
- 55 and the generally triangular section 12" of Figures 8 and 9 are preferably obtained by heating the tube and applying simple drawing or forming operations without blowing these connections or making them up separately and sealing to the remainder of the envelope.
- 60 For the purpose of further improving the action of the device, the bottom surface 30 (Figure 6) of the make and break connection 120
- 65 may be raised or humped slightly, as indicat-

ed. This raised portion 30, which may also be drawn or formed in the wall of the tube in the manner of the connection 12, is preferably disposed at the make and break point 20 and may be rounded as shown. In operation, the mercury or other conducting body makes and breaks over the raised surface or hump 30 and this raised surface tends to raise the actual section of separation and closing together of the ends 25 of the mercury body 75 above the bottom surface 32 of the tube further than possible with the lower surface 32 in substantially the same plane and without the hump 30. This raising of the make and break point of the switch further above the surface 80 32 secures a further increase in the effective force of gravity in separating the two mercury bodies after the break has occurred, due to the fact that just after the break the cohesive force of the mercury is released and 85 the bodies separate by moving down the relatively steep sides of the hump. This construction further reduces the effect of heat and arcing upon this surface.

In the present case, as in the Roth application referred to, the make and break is preferably over a sweeping or major radius, as distinguished from a relatively sharp or localized corner.

In the embodiment of Figures 1 and 2, the 95 tube 10 is shown mounted upon a support 35.

The tube 10 may be releasably attached to the support 35 by means of spring clips 36, suitably secured to the support and embracing the tube to support the same upon the 100 support 35 and against movement relative thereto.

Pivoted at 40 and 41 to the opposite ends of the support 36 are a pair of link members 42 and 43, which link members cross one another 105 at 44 and have fixed pivotal support at their lower ends at 45 and 46, respectively. An actuating arm or link 48 is pivoted at 49 to the link 43 and this link 48 may be suitably connected with the thermostat or other actuating 110 means for the switch.

To tilt the switch from closed circuit position, shown in Figure 1, to open circuit position, the actuating force is applied in the direction of the arrow in Figure 1. This 115 swings each of the link members 42 and 43 in a clockwise direction about their respective pivots 45 and 46 and, with this swinging action, the end of the support pivoted to the upper end of the link 43 is lowered and the 120 opposite end of this support is simultaneously raised by the pivotal connection with the upper end of the link 42. This crossed linkage 42, 43 reduces by one-half the amount of movement necessary to obtain a certain 125 tilting movement of the bulb, or with the same actuating movement, it is adapted for substantially doubling the amount of tilting movement imparted to the bulb.

In the embodiment of Figures 8 and 9, the 130

legs 11' of the tube 10' converge slightly toward their closed ends and the electrodes 16' and 17' are shown as entering the ends of these legs and extending internally of the legs 5 to the desired points therein.

In this embodiment, the make and break connection 12' is shown of generally triangular section with the rounded apex 52 at the bottom (Figure 9). This triangular section 10 of the make and break connection of the tube is adapted for narrowing the width of this connection with the advantages set out in connection with the embodiment of Figures 1 to 7, and at the same time, the triangular section 15 is adapted for increasing the internal section of this connection and for providing a constant bottom radius at 52, which may be the same for all tubes over, say, three-sixteenths inch diameter. I find that a one-eighth inch inside diameter at the make and break connection of the tube gives the most desirable meniscus and with this formation, this diameter or any suitable diameter may be provided at 52, regardless of the cross-sectional dimension of the connection 12'.

In Figure 11, the switch tube is indicated at 80 with a suitable heater indicated at 81 and a duct or passage 82 leading from the top of one end of the tube to a chamber 83. The 30 mercury within the tube is indicated at 84 and the heater is adapted for applying sufficient heat to the tube to form mercury vapor therein, which is exhausted through the conduit 82 to the chamber 83. It is to be understood that only a slight percentage of the mercury need be vaporized and the amount of mercury placed in the tube before this operation may be sufficient to compensate for this. This vaporization and exhaustion of 35 mercury vapor provides a better and more complete evacuation of the tube than heretofore possible and the mercury may be recovered from the chamber 83 as by collection in a settling chamber and distilling or in any 40 other suitable or preferred manner.

It is to be understood that, before the mercury vaporization operation, the tube may be exhausted with the usual pump, as heretofore, or the evacuation might be produced 45 solely by the mercury vaporization operation, as described. Upon completion of this evacuating operation, the conduit connection 82 is removed and the tube may be sealed at 85.

I do not intend to be limited to the precise 50 details shown or described.

I claim:

1. In a liquid switch having a conducting liquid body and adapted for opening and closing movement, a curved tube for holding and sealing the liquid body, said tube having a circuit making and breaking connection, and a pair of liquid receiving and conducting legs angularly disposed relative thereto for receiving and permitting rescission of the liquid from said circuit making and breaking

connection in opening the switch and toward said connection in closing the switch, said circuit making and breaking connection having a wall adapted for separating the liquid body into separate liquid bodies in the opening movement of the switch, and each of said separate liquid bodies being movable in opposite directions in said legs for movement away from each other in the opening movement of the switch and toward each other in closing movement of the switch, the walls of said circuit making and breaking connection at the point of break being brought closer together to form a reduced symmetrical section. 70

2. In a liquid flow switch having a conducting liquid body and adapted for opening and closing movement, a curved tube for holding and sealing the liquid body, said tube having a circuit making and breaking connection, and a pair of liquid receiving and conducting legs angularly disposed relative thereto for receiving and permitting rescission of the liquid in both legs from said circuit making and breaking connection in opening the switch and toward said connection in closing the switch and said tube being of elongated cross-section along the circuit making and breaking connection for flattening the meniscus of the liquid along said connection, the cross section of said legs being larger than said elongated cross section. 80

3. In a liquid flow switch having a conducting liquid body and adapted for opening and closing movement, a tube for holding and sealing the liquid body, said tube having a circuit making and breaking connection, and a pair of liquid receiving and conducting legs angularly disposed relative thereto for receiving and permitting rescission of the liquid from said connection in opening the switch and toward said connection in closing the switch, and the inner surface of said tube being humped along said circuit making and breaking connection to increase the speed of separation of the liquid. 100

4. In a liquid flow switch having a conducting liquid body and adapted for opening and closing movement, a tube for holding and sealing the liquid body, said tube having a circuit making and breaking connection, and a pair of liquid receiving and conducting legs angularly disposed relative thereto for receiving and permitting rescission of the liquid from said circuit making and breaking connection in opening the switch and toward said connection in closing the switch and said tube being of elongated cross-section along the circuit making and breaking connection for flattening the meniscus of the liquid along said connection, and the inner surface of said tube being humped along said connection to space the region of make and break from the wall of the tube. 110

5. In combination, a liquid flow switch, a 120

support therefor, linkage comprising a pair of cross links, each pivoted at one end to said support and having fixed pivotal support adjacent its opposite end, and actuating means 5 having connection with said linkage.

6. In combination, a liquid flow switch, actuating means for tilting said switch, and a linkage connection between the switch and said actuating means and comprising crossed 10 link means for lowering one end of the switch and link means for simultaneously raising the opposite end of the switch and vice versa.

7. A liquid flow switch having a conducting liquid body movable to open and 15 closed circuit positions and comprising the combination with said liquid body of tilting means for confining and separating the body of conducting liquid into two separate bodies each movable away from the other when the 20 confining means is tilted, said means having a region which has no inclination regardless of the tilt and being formed with a raised portion centrally thereof so that as the broken ends of the liquid body separate the effective 25 force of gravity acting to separate them is increased.

8. In combination, a liquid flow switch, a support therefor, linkage comprising a pair of links, each pivoted near one end to said support 30 and at spaced apart points, said links having fixed pivotal support adjacent their opposite ends and at spaced apart points, the distance between one pair of pivots being different from the distance between the other 35 pair, and actuating means having connection with said linkage.

9. A liquid flow switch comprising a tubular holder for the liquid body affording a generally U-shaped passage for holding and 40 conducting the switch liquid, the cross section of said passage at the central portion being narrower relative to the other portions of the passage and the invert of said central portion having a slope steeper than the other 45 portions of the passage when the tubular holder is horizontal.

In witness whereof, I hereunto subscribe
my name this 23rd day of April, 1929.

ADIEL Y. DODGE.
